(57) **CLAIM**

The ornamental design for a fretboard label for six-stringed instruments and simulators thereof, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a plan view of the claimed fretboard label for six-stringed instruments and simulators thereof, showing our new design;

FIG. 2 is a partial top plan view of the upper portion of FIG. 1 up to line [y-y];

FIG. 3 is a partial right side elevational view of the upper portion of FIG. 1 up to line [y-y];

FIG. 4 is a partial top plan view of the middle portion of FIG. 1 between line [y-y] and line [x-x];

FIG. 5 is a right side elevational view of the middle portion of FIG. 1, between line [y--y] -and line [x--x];

FIG. 6 is a partial top plan view of the lower portion of FIG. 1, from line [x-x]; and,

FIG. 7 is a partial right side elevational view of the lower portion of FIG. 1 from line [x-x].

The dot-dash-dot lines indicate the connection between the partial views and form no part of the claimed design thereof. The dot-dot-dash lines indicate environmental features only and form no part of the claimed design thereof.

1 Claim, 4 Drawing Sheets
